[57] **CLAIM**

The ornamental design for the decorative light for a light string, as shown and described.

DESCRIPTION

FIG. 1 is a perspective view of the decorative light for a light string seen from its front showing my new design;

FIG. 2 is a right-hand side view thereof;

FIG. 3 is a left-hand side view thereof;

FIG. 4 is a plan view thereof;

FIG. 5 is a front view thereof;

FIG. 6 is a bottom view thereof;

FIG. 7 is a rear view thereof;

FIG. 8 is a perspective view thereof on a reduced scale, the light string being shown in broken lines for illustrative purposes only; and,

FIG. 9 is a sectional view thereof cut at the center line of the plan view in its lateral direction.

FIG. 1

FIG. 2
